R. B. VINCENT

PAINT REMOVER

Filed Oct. 3, 1923

Robert B. Vincent
By Adam E. Fisher
J.G. Attorney

UNITED STATES PATENT OFFICE.

ROBERT B. VINCENT, OF KEOKA, IOWA.

PAINT REMOVER.

Application filed October 3, 1923. Serial No. 666,340.

To all whom it may concern:

Be it known that ROBERT B. VINCENT, a citizen of the United States, residing at Keota, in the county of Keokuk and State of Iowa, has invented certain new and useful Improvements in Paint Removers, of which the following is a specification.

This invention is in the way of a paint remover, and the object of the invention is to provide a simple, practical and efficient device of this kind for scraping and removing old paint from painted surfaces.

In the drawing—

Figure 1 is a side elevation of the device; Figure 2 is a longitudinal vertical section; Figure 3 is a bottom plan view;

Figure 4 is a view of the blank stamping for the housing.

In carrying out this invention, a housing 20 1 is provided, the same to be stamped from a single sheet of metal as shown in Figure 4. To form the housing, the forward end of the sheet metal is bent outward and downward to form the scraper 2; the rear 25 strip is bent upward at 3 and forward to form the handle 4. The edges 5 of the rear strip are turned under so as to strengthen the handle. The side pieces are turned downward at 6 to form the side 7 of the housing. Ears 8 are formed integrally with the sides 7 and are slotted at 9 to receive the brush shaft 10. Shafts 11, 12 and 13 are journaled through the housing. Driving rollers 14 are rigidly mounted on the drive shaft 11. A driving gear 15 is rigidly mounted on the shaft 11 and meshes with the pinion gear 16 rigidly mounted on the shaft 12. A gear 17 mounted on the shaft 12 and formed integrally with the pinion gear 16, meshes with the small gear 18 rigidly mounted on the shaft 13. A sprocket wheel 19 is also rigidly mounted on the shaft 13. A rotary brush 20 is mounted on the brush shaft 10 and is rotated by means of the sprocket wheel 21, which is connected with the sprocket wheel 19 by means of a sprocket chain 22.

The operation of the device is apparent from the foregoing description.

While I have herein described a certain specific manner and method of constructing and assembling the elements of my invention, it is understood that I may vary from the same in minor details, not departing from the spirit of my invention, so as best to construct a practical device for the purpose intended, as defined in the appended claims.

I claim:

1. A paint remover, comprising a sheet 60 metal housing having an upwardly turned handle, a forwardly disposed downwardly turned scraping element, and downwardly turned lateral and slotted ears immediately back of the scraping element, all formed integrally with the housing; a brush shaft journaled in the slotted ears; a rotary brush and a sprocket wheel on the brush shaft; a drive shaft journaled transversely at the rear end of the housing; driving rollers 70 and a drive gear on the drive shaft; shafts with intermeshing speed gears journaled between the drive shaft and brush shaft, and in mesh with the said drive gear; a sprocket on the foremost shaft aligned with 75 the sprocket of the brush shaft; and a sprocket chain connecting the two said sprockets.

2. A paint remover, comprising a housing having a handle, and a scraping element 80 formed integrally with the housing; a forwardly disposed brush shaft and a rearwardly disposed drive shaft journaled transversely in the housing; a rotary brush on the brush shaft and driving rollers on the driving shaft; and connecting gearing operatively interposed between the brush shaft and the drive shaft.

In testimony whereof I affix my signature.

ROBERT B. VINCENT.

Witnesses:

H. G. RICHARDSON,
ED. HAMMEN.
